E. G. LOVELACE

HEDGE TRIMMER

Filed April 18, 1923.

BY *E.G. Lovelace*
Wilson E. Coleman
ATTORNEY.

UNITED STATES PATENT OFFICE.

EUGENE G. LOVELACE, OF HIGH POINT, NORTH CAROLINA, ASSIGNOR OF ONE-FOURTH
TO TOM GIANOULIS AND ONE-FOURTH TO R. J. WAGGER, BOTH OF HIGH POINT,
NORTH CAROLINA.

HEDGE TRIMMER.

Application filed April 18, 1923. Serial No. 632,899.

To all whom it may concern:

- Be it known that I, EUGENE G. LOVELACE, a citizen of the United States, residing at High Point, in the county of Guilford and State of North Carolina, have invented certain new and useful Improvements in Hedge Trimmers, of which the following is a specification, reference being had to the accompanying drawings.
- 10 This invention relates to certain improvements in hedge trimmers and it is an object of the invention to provide a novel and improved device of this general character wherein the reciprocating cutter or blade is carried by a head, said head being capable of adjustable connection with a supporting member whereby the hedge may be trimmed at a side or cut at any special angle as may be desired.
- 15 It is also an object of the invention to provide a novel and improved device of this general character embodying means whereby a handle or hand grasp may be arranged in different positions as best suits the convenience of the operator.
- 20 Another object of the invention is to provide a novel and improved device of this general character wherein the crank and its connection with the reciprocating cutter are 25 encased or enclosed so that hindrance or obstruction will not be offered thereto during a working operation.
- The invention consists in the details of construction and in the combination and arrangement of the several parts of my improved hedge trimmer whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in plan with a portion broken away of a hedge trimmer constructed in accordance with an embodiment of my invention;

Figure 2 is a view partly in side elevation and partly in section of the structure as illustrated in Figure 1;

Figure 3 is a sectional view taken substantially on the line 3—3 of Figure 1.

As disclosed in the accompanying drawings, 1 denotes an elongated rod or member provided at its outer end with a cross head 2 to facilitate the operation of the device. 60 The opposite end portion of the rod or member 1 is connected with a bracket 3 which is also connected with an elongated tubular member 4, said members 4 and 1 being longitudinally aligned.

Rotatably supported by the bracket 3 is a pinion 5 meshing with a gear wheel 6, said gear wheel 6 being rotatably supported by a bearing 7 of the member or rod 1 at a point in relatively close proximity to the bracket 3. The gear wheel 6 is provided with an operating crank 8 whereby the same may be manually operated.

Carried by the bearing 7 and disposed in a direction away from the gear wheel 6 is a handle or hand grasp 9. If preferred however this handle or hand grasp 9 may be disposed in a position substantially parallel with the rod or member 1 and in order to provide for such mounting the end portion of the bracket 3 immediately adjacent to the member or rod 1 is provided with the outstanding and perpendicularly related arm 10 arranged at the side of the bracket 3 opposite to the gear wheel 6. The handle member 9 may be readily secured in a conventional manner to the outer end portion of said arm 10. The pinion 5 is fixed to the inner end portion of a shaft 11 which extends entirely through the member 4 and terminates a desired distance outwardly thereof for a purpose to be hereinafter more particularly referred to.

The cutting mechanism proper comprises a head H comprising a pair of overlying sections 12 and 14 and said head H is provided with the outstanding fingers 15 of a conventional type.

The sections 12 and 14 are maintained in overlying or assembled relation through the 100 instrumentality of the holding screws 16 or the like.

The head H at the central portion thereof and at its rear is provided with an outstanding extension 17 providing a chamber 18. 105 The chamber 18 adjacent one end is provided with an outstanding boss 19 the bore of which being in communication with the

chamber 18. The boss 19 has threaded thereon a nut 20 provided at its outer end with an inwardly directed flange 21 freely surrounding the member 11 and adapted to have contact with the inner face of the outstanding annular shoulder 22 carried by the outer end of the member 11. The nut 20 is also provided with the outstanding preferably diametrically opposed arms 23 to facilitate the rotation thereof. The nut 20 provides means whereby the head H is coupled to the outer end of the member 11.

When the head H is applied to the member the shaft 11 extends through the boss 19 and partially within the chamber 18. The inner portion of the boss 19 having inserted therein a bearing 24 for said shaft.

Fixed to the extremity of the shaft 11 within the chamber 18 is a crank disc 25 in which is operatively engaged a pitman 26. The pitman 26 is also operatively engaged as at 27 with the cutting knife or blade 28 of a conventional type wherein the outstanding teeth 29 are employed.

As is particularly illustrated in Figure 1 it is to be noted that the crank 25 and the pitman 26 at all times are housed or contained within the chamber 18 so that said parts are effectively protected against hindrance or obstruction during a working operation. It is also to be noted that the chamber 18 is of a length to permit the blade 28 to have requisite stroke which is sufficient to cause the teeth 29 of said blade to travel across the spaces between adjacent fingers 15.

By loosening the nut 20 the head H can be readily turned or adjusted to any desired angle with respect to the member 11 whereby a hedge may be readily trimmed at the sides or at any angle desired and that said adjustment will be effectively maintained upon tightening of the nut 20. This adjustment of the head H in one way effects the normal or general handling of the implement and my improved trimmer is therefore particularly adapted for use by persons unskilled or inexperienced in the trimming of hedges.

From the foregoing description it is thought to be obvious that a hedge trimmer constructed in accordance with my invention is particularly well adapted for use by reason of the convenience and facility with which it may be assembled and operated, and it will also be obvious that my

invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. An implement of the class described comprising a head, a reciprocating cutting blade associated therewith, a tubular member, means for coupling the head to the tubular member, said head being adjustable about the tubular member as an axis, said coupling means operating to hold the head fixed with respect to the tubular member, and means for reciprocating the blade.

2. An implement of the class described comprising a head, a reciprocating cutting blade carried thereby, said head being provided at its rear with a chamber, an outstanding tubular boss having its bore in communication with the chamber, a nut threaded on the boss and provided at its outer end with an inwardly directed flange, a tubular member, said nut being freely engaged with the tubular member, said tubular member being provided with an outstanding flange inwardly of the flange of the nut whereby the tubular member and boss are held in fixed relation, a shaft extending through the tubular member and through the boss within the chamber, means for rotating the shaft, and an operative connection within the chamber between the shaft and the cutting blade for reciprocating the cutting blade upon rotation of the shaft.

3. An implement of the class described comprising a head, a reciprocating cutting blade associated therewith, said head rearwardly of the blade being provided with a chamber, a tubular member, means for connecting the tubular member to the head, said tubular member when applied being in communication with the chamber, a shaft disposed through the tubular member and extending within the chamber, means for rotating the shaft, and an operative connection within the chamber between the shaft and the cutting blade for reciprocating the cutting blade upon rotation of the shaft.

In testimony whereof I hereunto affix my signature.

EUGENE G. LOVELACE.
